UNITED STATES PATENT OFFICE.

AUGUST WENGENROTH, OF WEST HOBOKEN, NEW JERSEY, ASSIGNOR OF ONE-THIRD TO FREDERICK AUGUST ARBENZ, OF WEST HOBOKEN, NEW JERSEY.

FURNACE FOR LIQUID FUEL.

SPECIFICATION forming part of Letters Patent No. 723,564, dated March 24, 1903.

Application filed December 3, 1902. Serial No. 133,771. (No model.)

To all whom it may concern:

Be it known that I, AUGUST WENGENROTH, of the city of West Hoboken, county of Hudson, and State of New Jersey, have invented 5 certain new and useful Improvements in Furnaces for Liquid Fuel, of which the following is a full, clear, and exact specification, reference being had to the accompanying drawings, wherein—

10 Figure 1 is a longitudinal sectional view of a boiler-furnace constructed according to my invention. Fig. 2 is a cross-sectional view on line 2 2 indicated in Fig. 1 looking to the right. Figs. 3 and 4 are elevations of parts 15 of my improved fuel-conduit, and Fig. 5 is an elevation of a boiler-furnace constructed according to my invention. In this last figure part of the front wall of the furnace is broken off to show the arrangement of the fuel-conduits within the furnace.

15 My invention relates to furnaces and heating appliances; and it consists of the herein-after-described construction of a liquid-fuel conduit and in the combination of it with 20 other parts in the construction of a furnace or heating apparatus.

25 Referring to the drawings, numeral 1 designates a liquid-fuel conduit, and 2 a steam or compressed-air conduit, as are generally used 30 in such cases.

35 3 designates cocks governing the flow of the fuel into the burners.

4 is a supporting-bar, whereon my improved liquid-fuel conduit is supported.

35 5 is a trough or drip-pan for gathering the overflow of the liquid fuel.

The mixing or carbureting apparatus (shown in sectional view in Fig. 1) consists of a chamber 6, secured to the air-conduit, 40 as will be seen in Fig. 5, subdivided by web 7 into two compartments *a* and *b*, nozzles 8 and 9, and needle-valve 3. Compartment *a* of chamber 6 connects with the oil-conduit and compartment *b* with the conduit for steam 45 or compressed air. Compartment *b* is connected by nozzle 8 with the fuel-conduit A within the furnace. Nozzle 9, screwed in the web 7 and set concentrically with nozzle 8, discharges the oil in a spray into nozzle 8, 50 whence the same is carried by the current of

air or steam into the conduit in the fuel-conduit within the furnace. Some of the known devices may be employed for dispersing the flow of the liquid fuel, (atomizing;) but this is not essential to the working of my invention. 55 Needle-valve 3 is provided for regulating the flow of the liquid fuel.

The fuel-conduit located in the furnace or heating apparatus is composed, preferably, of fireproof brick material made up in sections, 60 as shown in Figs. 3 and 4, these sections being provided with alternating recesses, whereby the sections when joined longitudinally interlock with each other, as shown in Fig. 1. Each section consists of a base-piece 10 and 65 top piece 11. Base-piece 10 is formed in the shape of a trough, being provided with a semicircular depression 12 on its upper face. Top piece 11 is provided with a deep longitudinal channel or groove 13 and with shallower 70 semicircular grooves 14, arranged transversely at intervals. In addition thereto perforations 15, distributed at intervals and alternating with grooves 14, are provided in these top pieces. Channel 13 of the last section is 75 closed on its end.

When constructing a furnace according to my invention, the sections of the conduit are placed on beams 4 or other suitable supports and joined together, as shown in the drawings. 80 The interlocking joints between the sections are sealed and secured together with fireproof cement. Then nozzle 8 is connected to channel 13 of the first section and the joint hermetically sealed. The drip-pan is then set 85 in position, and some distance above its bottom apertures for draft air and dampers are arranged.

When starting the furnace, a light wood fire is lighted in the furnace and then the liquid-fuel apparatus is set in action. The force of the compressed air, steam, or other medium drives the carbureted liquid fuel through channel 13, channels 14, and perforations 15 into the furnaces, where it is consumed, each 90 orifice of the conduit acting as a blowpipe-burner, producing what is known as the "blue flame," but owing to the large number of the apertures through which the carbureted fuel is conducted into the furnace the pressure 95 100

on the fuel is correspondingly distributed and reduced and there is only a comparatively low flame produced at each of the many outlets of the conduit. Consequently the 5 overheating of the boiler in one place, which heretofore was the most serious defect of apparatuses for burning liquid fuel, is avoided.

I have conducted a long series of tests when 10 devising the hereinbefore-described apparatus and found that by constructing and arranging the fuel-conduit in the furnace as I have explained a flame is obtained in the furnace almost identical with the flame of the coal when burned with forced draft and that 15 every portion of the boiler within the furnace is uniformly heated.

I claim as my invention—

1. A conduit for liquid fuel, composed of a 20 trough-like base, having a semicircular depression in its upper face, and of a top piece fitted into the base, and having a longitudinal groove approximately in its center, of 25 transverse grooves at intervals, and perforations, communicating with the longitudinal groove, substantially as herein shown and described.

2. A conduit for liquid fuel, composed of a trough-like base, having a semicircular depression on its upper face, and of a top piece fitted into the base, and having a longitudinal groove approximately in its center, of 30 transverse grooves at intervals, and perforations, communicating with the longitudinal groove, and alternating with the transverse grooves, substantially as herein shown and 35 described.

3. A furnace for boilers and heating apparatuses, comprising the combination with an apparatus for mixing liquid fuel and compressed air or steam, of a conduit composed 40 of a trough-like base, having a semicircular depression on its upper face, and of a top piece fitted into the base and having a longitudinal groove approximately in its center, of 45 transverse grooves at intervals, and perforations, communicating with the longitudinal groove, substantially as herein shown and described.

AUGUST WENGENROTH.
